BOTTLE OR SIMILAR ARTICLE

John F. Sanford, Great Neck, N. Y.

Application August 17, 1953, Serial No. 26,472

Term of patent 14 years

(Cl. D58—9)

To all whom it may concern:

Be it known that I, John F. Sanford, a citizen of the United States of America, residing at Great Neck, in the county of Nassau and State of New York, have invented a new, original, and ornamental Design for a Bottle or Similar Article, of which the following is a specification, reference being had to the accompanying drawing, forming a part thereof.

Fig. 1 is a front elevational view of a bottle or similar article, showing my new design.

Fig. 2 is a top plan view thereof.

Fig. 3 is a side elevational view thereof.

Fig. 4 is a bottom plan view thereof.

I claim:

The ornamental design for a bottle or similar article, substantially as shown.
